UNITED STATES PATENT OFFICE.

GEORGE H. WHITTINGHAM, OF PIKESVILLE, MARYLAND, ASSIGNOR TO MONITOR
MANUFACTURING COMPANY OF BALTIMORE CITY, OF BALTIMORE, MARYLAND,
A CORPORATION OF MARYLAND.

MOTOR-STARTER.

1,135,870.

Specification of Letters Patent. Patented Apr. 13, 1915.

Application filed September 29, 1911. Serial No. 652,019.

To all whom it may concern:

Be it known that I, GEORGE H. WHITTINGHAM, a citizen of the United States, residing at Pikesville, in the county of Baltimore and State of Maryland, have invented certain new and useful Improvements in Motor-Starters, of which the following is a specification.

This invention relates to starters for electric motors of the kind in which the cutting out of the starting resistance is controlled by the quantity of current flowing in the armature circuit.

In carrying out my invention an electromagnetic switch is provided for each section of starting resistance, this switch comprising a series magnet, having its windings in series with the motor armature, a holding magnet having its windings in a circuit independently of the armature circuit of the motor, and a rocking armature pivoted between its ends and normally biased toward the pole-piece of the series magnet, the arrangement being such that when the motor circuits are first closed the series magnet will hold the rocking armature until the starting current falls to a predetermined amount; when the holding magnet will attract the armature and the switch contacts will be thereby closed and held together with considerable pressure, the holding magnet operating like a spring to close the switch. When the current is cut off the rocking armature is released from the holding magnet and swings, by gravity, toward the pole-piece of the series magnet, thus opening the switch.

The invention also includes means for regulating the reluctance of the magnetic circuit, to control the time of closure of the switch, and means for cutting down the current flow in the holding magnet after the switch has closed, in order to avoid heating of the latter magnet, which, if permitted, would change its resistance relatively to the resistance of the series magnet and therefore change the time of closure of the switch in a subsequent operation.

In the accompanying drawing which illustrates my invention, — Figure 1 is a front elevation of one of the resistance-controlling switches; Fig. 2 is a side elevation of the same partly broken away, the switch being shown in closed position; Fig. 3 is a central

vertical section through the switch, showing the same in open position; Fig. 4 is an end view of the adjustable pole-piece, with the series coil surrounding the same; and, Fig. 5 is a diagrammatic view illustrating the starter with two steps of starting resistance.

Referring to Figs. 1 to 4, inclusive, of the drawing, A indicates, as a whole, one of the electromagnetic switches for cutting out starting resistance, which is mounted upon a suitable insulating base or panel B, and C indicates an iron frame or base secured to the panel and having projecting therefrom an upper pole-piece c a central pole-piece c' and a lower pole-piece c^2 . The upper pole-piece is surrounded by a coil 1 of fine wire, having considerable resistance, and the lower pole piece is provided with a coil 2, of coarser wire and low resistance. An iron armature D is pivoted, between its ends, upon a pin 3 passing through ears 4 on the armature and 5 on the central pole-piece. The armature tends to swing by gravity away from the pole piece c and toward the pole-piece c^2 but it is normally held out of engagement with the latter pole-piece by a tubular stop 6, preferably of non-magnetic material, which surrounds the pole-piece. The pole piece c^2 comprises a tubular part 7, integral with the base C, and a rod or bolt 8 having a threaded connection with the part 7, the part 8 being adjustable relatively to the stop 6 so that the distance of the pole-piece from the armature may be regulated to vary the attractive force of the series magnet upon the armature. The bolt 8 has one or more slots 8^a extending diametrically through it, the bolt in the drawing being shown with two such slots. A cotter pin 9 extends diametrically through the tubular stop 6 and through one of the slots 8^a in the adjustable pole-piece and therefore locks the latter in its position of adjustment. By removing the armature and turning the pole-piece 8 by means of a screw driver inserted in one of the slots 8^a, the air gap between the pole-piece and the armature may be adjusted as desired, and as two slots are provided in the pole-piece, it will be evident that the latter may be locked by the cotter pin at any quarter turn. The cotter pin also serves the purpose of retaining the series coil upon the pole-piece. A cop-

per cross piece 10, secured to the upper end of the armature, carries contacts 11, adapted to engage suitable stationary contacts 12 when the switch is closed.

5 The circuit connections of a two step motor are illustrated in Fig. 5, wherein A' and A² indicate resistance-controlling switches of the kind heretofore described, and 12^a, 12^b, 12^c and 12^d indicate the stationary contacts 10 of such switches, these contacts, in the diagram, being shown above the cross bars 10 in order to indicate the open positions of the switches. The switch for connecting the starter, and the motor M with the supply circuit is indicated at S and the armature circuit of the motor extends from the stationary contact 13 of said switch, through conductor 14, series coil 2^a, and section of starting resistance 15, series coils 2^b, and section of starting resistance 16, and thence through the motor armature 17 to the negative supply wire. The coils of the holding magnets of the resistance-controlling switches are in a circuit 19 which extends from a stationary contact 18, on the switch S, through the holding coils 1^a and 1^b, in series, and thence through a fixed resistance 20 to the negative side of the supply circuit. The total resistance of the circuit 19 is high, and normally only a small quantity of current passes through the holding coils of the switches. Another high resistance coil 21 is arranged so that when the switch A² closes this resistance will be connected in series with the resistance 20 and in shunt to the holding coils 1^a and 1^b, the resistance 21 being proportioned so that when thrown in circuit the current flowing through the holding coils of the switches will be very small 40 in quantity and not sufficient to cause the coils to heat. The supply circuit switch S comprises a pivoted arm 22 adapted, in closing, to first engage the contact 13 and close the armature circuit through the series coils 24 of the resistance-controlling switches, and then to engage the contact 18 and close the circuit 19 through the holding coils of said switches and through the resistance 20. The switch S is represented in the drawing as an electromagnetically-controlled switch, the magnet 23 of which is arranged in a circuit 24, connected at one end to the negative supply wire and a manual-controlled switch 25 is provided for connecting the circuit 24 with 50 the positive supply wire. The motor is shown with a shunt field 26, connected at one end to the negative supply wire and having its opposite end connected through conductors 27 and 14 to the contact 13.

55 In operation, when the manual switch 25 is closed, the magnet 23 is energized and the switch arm 22 is attracted thereby and first engages the contact 13 and then engages the contact 18. When the contact 13 is engaged current flows through the conductor

27 and the field of the motor and it also flows through the series coils 2^a, 2^b and the starting resistance sections 15 and 16 and through the motor armature 17. The rocking armatures D of the switches normally rest against the tubular stops 6, and closer to the pole-pieces of the series magnets than to the pole-pieces of the holding magnets. Hence these armatures will be strongly attracted by the series magnets which carry the entire starting current. Immediately after the closure of the armature circuit, the switch S closes the circuit 19 through the holding magnets and the resistance 20, and these magnets also exert an attractive force on the armatures D, but insufficient to rock the same away from the series magnets so long as the starting current remains above predetermined limits. It will be noted that the projection c' upon which the armature D of each resistance-controlling switch is mounted, is a part of the magnetic circuit of both the series and holding magnets; but the heavy magnetic flux created by the current in the series coil, when the starting current is a maximum, practically saturates the common pole-piece c', and by properly connecting the coils the flux created by the series coil may be made to oppose the flux set up by by the holding coil so that while the starting current is a maximum the attractive force of the holding coil upon the armature will be small, whereas when the current in the series coil falls this opposition of the magnetic fluxes will be correspondingly reduced and the holding coil will attract with greater force as the current in the series coil diminishes.

In Fig. 3, the dotted lines and arrows s and h indicate the opposing magnetic fluxes set up by the current in the series and holding coils, respectively. When the starting current falls to a predetermined amount, the attractive force of the series magnet 2^a of the switch A' will be overcome by the attractive force of the holding coil 1^a and the armature will be moved by the latter magnet to close the switch, the bridge piece 10 of which will then connect the stationary contacts 12^a and 12^b. Current will then flow from the contact 13, through conductors 27 and 28 to the contact 12^a, thence through bridge piece 10 and contact 12^b and through conductor 29 to an intermediate portion of the coil 2^b of the switch A², thence through a portion of said coil and through resistance section 16 to the armature. The series coil 2^a of the switch A', the resistance section 15 and a portion of the series coil 2^b will then be short circuited and the switch A' will be held closed by the shunt magnet 1^a. After the temporary rise in current which follows the cutting out of this first resistance section, as the motor armature gains speed, the armature current will again fall. When it falls to a predetermined 130

mined quantity the series coil 2^b of the switch A² will be overpowered by the holding coil 1^b of such switch and the switch will then close, connecting the contacts 12^c and 12^d.
 5 The armature current will then flow from contact 13 through conductors 27 and 30, contact 12^c, bridge-piece 10 and 12^d and conductor 31 to the motor armature, the resistance section 16 and the remaining windings of the series coils 2^b being short circuited.
 10 The armature D of the switch A² will be held closed by the holding coil 1^b.

As previously stated the total resistance of the circuit 19, including the high resistance holding coils 1^a and 1^b and high resistance 20, is such, as compared with the voltage of the supply circuit, that the current which flows initially through the holding coils is small, being only a fraction of an ampere and insufficient to heat the coils during the starting interval. When the switch A² closes the high resistance coil 21 is connected in parallel with the holding magnets and in series with the high resistance coil 20. As shown in the drawing the high resistance 21 is connected by the conductor 32 to the wire 19 between the resistance 20 and the holding coil 1^b, and the opposite end of the resistance coil 21 is connected by a conductor 33 to the armature D of the switch A². It will be seen that as soon as the switch A² closes the conductor 33 will be connected through the bridge piece 10 to the contact 12^c and thence through conductors 30, 27 and 14 to the contact 13 and thence through the switch arm 22 to the positive supply wire. Thus the limited quantity of current passing through the resistance 20, becomes divided between the circuit 19, which includes the holding coils, and the circuit which includes the resistance 21 and the current flowing through the holding coils will be reduced to a very small quantity, but sufficient to hold the switches in their closed positions with firm contacts. Whenever the manual switch 25 is opened, it will be evident that the switch S will be released by its magnet 23 and the motor circuits will thereby be opened and the armatures D will fall by gravity away from the holding magnets 1^a and 1^b toward the series magnets, thus causing the starting resistance to be reinserted in the armature circuit of the motor. In this switch it is important to prevent heating of the holding coils, as an increase in resistance due to heating would prevent the normal current from flowing through the coils of the holding magnets, in starting, and hence would decrease the attractive power of these magnets and destroy the adjustment, since the time of closure of the switches is controlled by the relative attractive forces of the holding and series magnets.

For convenience, the magnets having their 65 windings in series with the armature of the

motor will be referred to in the claims as series magnets, and the magnets having their windings in a circuit independent of the armature circuit will be referred to as holding magnets.

What I claim is:—

1. The combination with an electric motor and its circuits, including a starting resistance in the armature circuit thereof, of a switch for cutting out said resistance comprising a rocking magnetizable arm, pivoted between its ends, for opening and closing the switch contacts, two magnets having stationary pole pieces arranged adjacent said rocking arm on opposite sides of its pivotal axis and adapted to oppositely attract the arm, one of said magnets having low resistance windings in series with the motor armature and the starting resistance and the other having high resistance windings in a separate circuit, said arm being biased toward the former magnet, and means for opening and closing the circuits through said magnets.

2. The combination with an electric motor 90
and its circuits, including a starting resist-
ance in the armature circuit thereof, of a
switch for cutting out said resistance com-
prising a rocking magnetizable arm, pivoted
between its ends, for opening and closing 95
the switch contacts, two magnets having sta-
tionary pole pieces arranged adjacent said
rocking arm on opposite sides of its pivotal
axis and adapted to oppositely attract the
arm, one of said magnets having low re- 100
sistance windings in series with the motor
armature and the starting resistance and the
other having high resistance windings in a
separate circuit, said arm being biased to-
ward the former magnet, means for varying 105
the reluctance of the magnetic circuit
through one of said magnets and said arm,
and means for opening and closing the cir-
cuits through said magnets.

3. The combination with an electric motor 110 and its circuits, including a starting resistance in the armature circuit thereof, of a switch for cutting out said resistance comprising a rocking magnetizable arm, pivoted between its ends, for opening and closing the 115 switch contacts, two magnets having stationary pole pieces arranged adjacent said rocking arm on opposite sides of its pivotal axis and adapted to oppositely attract the arm, one of said magnets having low resistance 120 windings in series with the motor armature and the starting resistance and the other having high resistance windings in a separate circuit, said arm being biased toward the former magnet, means for varying the 125 reluctance of the magnetic circuit through the core of the magnet having low resistance windings and said arm, and means for opening and closing the circuits through said magnets. 130

4. The combination with an electric motor and its circuits, including a starting resistance in the armature circuit thereof, of a switch for cutting out said resistance comprising a magnetizable arm, pivoted between its ends, for opening and closing the switch contacts, two magnets having stationary pole pieces arranged adjacent said rocking arm on opposite sides of its pivotal axis 10 and adapted to oppositely attract the arm, one of said magnets having low resistance windings in series with the motor armature and the starting resistance and the other having high resistance windings in a separate circuit, the core of the magnet having low resistance windings being adjustable in length and said arm being biased toward said magnet, a stop for limiting the movement of the arm toward the latter core, and 20 means for opening and closing the circuits through said magnets.

5. The combination with an electric motor and its circuits, including a starting resistance in the armature circuit thereof, of a switch for cutting out said resistance comprising a magnetizable arm pivoted between its ends to rock in a vertical plane, two magnets having stationary pole pieces arranged respectively above and below the 30 axis of said arm and adapted to oppositely attract the arm, the lower magnet having low resistance windings in series with the motor armature and starting resistance, and the upper magnet having high resistance 35 windings in a separate circuit, said arm being biased toward the lower magnet, and means for opening and closing the circuits through said magnets.

6. The combination with an electric motor and its circuits, including a starting resistance in the armature circuit thereof, of a switch for cutting out said resistance comprising a magnetizable arm pivoted between its ends to rock in a vertical plane, two 45 magnets having stationary pole pieces arranged respectively above and below the axis on said arm and adapted to oppositely attract the arm, the lower magnet having low resistance windings in series with the motor armature and starting resistance, and the upper magnet having high resistance 50 windings in a separate circuit, said arm being biased toward the lower magnet, means for varying the reluctance of the magnetic circuit through the lower magnet and said arm, and means for opening and closing the circuits through said magnets.

7. The combination with an electric motor and its circuits, including a starting resistance in the armature circuit thereof, of a switch for cutting out said resistance comprising a magnetizable arm pivoted between its ends to rock in a vertical plane, two magnets having stationary pole pieces arranged 60 respectively above and below the axis of

said arm and adapted to oppositely attract the arm, the lower magnet having low resistance windings in series with the motor armature and starting resistance, and the upper magnet having high resistance windings 70 in a separate circuit, said arm being biased toward the lower magnet and the core of said lower magnet being adjustable in length, a stop for limiting the movement of the arm toward the latter core, and means 75 for opening and closing the circuits through said magnets.

8. The combination with an electric motor and its circuits, including a starting resistance in the armature circuit thereof, of a switch for cutting out said resistance comprising a magnetizable arm pivoted between its ends to rock in a vertical plane, two magnets having stationary pole pieces arranged respectively above and below the 80 axis of said arm and adapted to oppositely attract the arm, the lower magnet having low resistance windings in series with the motor armature and starting resistance, and the upper magnet having high resistance 85 windings in a separate circuit, said arm having a fixed range of movement and the core of the lower magnet being adjustable to vary the reluctance of the magnetic circuit through said latter core and said arm, and means 90 for opening and closing the circuits through said magnets.

9. The combination with an electric motor and its circuits, including a starting resistance in the armature circuit thereof, of means for cutting out the starting resistance comprising switch contacts, a base of magnetizable material having a central and two end pole pieces, a magnetizable switch arm for opening and closing the switch contacts, 105 said arm pivoted between its ends on the central pole piece, low resistance windings in series with the motor armature and the starting resistance on one end pole piece, high resistance windings in a separate circuit 110 on the other end pole piece, said arm being biased toward the pole piece having the low resistance windings, and means for opening and closing the circuits through the windings of said magnets.

10. The combination with an electric motor and its circuits, including a starting resistance in the armature circuit thereof, of means for cutting out the starting resistance comprising switch contacts, a base of magnetizable material having a central and two end pole pieces, a magnetizable switch arm for opening and closing the switch contacts, 120 said arm pivoted between its ends on the central pole piece, low resistance windings in series with the motor armature and the starting resistance on one end pole piece, high resistance windings in a separate circuit 125 on the other end pole piece, said arm having a fixed range of movement and being 130

biased toward the pole piece having the low resistance windings, and said latter pole piece being adjustable to vary the reluctance of the magnetic circuit through said latter pole piece and said arm, and means for opening and closing the circuits through the windings of said magnets.

11. Switch members and means for controlling the same comprising relatively high and low resistance magnets, an armature biased toward the low resistance magnet and adapted to close the switch when moved toward the high resistance magnet, an external

high resistance normally in series with the high resistance magnet and another external 15 high resistance adapted to be included in series with the first mentioned high resistance and in parallel with said high resistance magnet when said switch closes.

In testimony whereof I affix my signature 20 in presence of two witnesses.
